12 Claims. (Cl. 333—98)

This invention relates to devices having windows for transmitting high frequency electromagnetic power such as are required for sealing an evacuated device whilst at the same time permitting the transmission of high frequency power and for other purposes. Frequently electron discharge valves of the klystron or magnetron types have their vacuum envelopes sealed by such a window so as to enable a waveguide to be coupled to said window so that power can be transmitted from the valve to the waveguide. Such windows have heretofore usually been made of glass but it is found that when high powers are required to be handled by the valves difficulties arise in finding a satisfactory glass which can withstand the heat which is generated during transmission of high degrees of power. Moreover, if refractory materials capable of transmitting high frequency power are employed for such windows then it is also found that these windows give rise to reflections which it is found not only causes the oscillations generated in the klystron or magnetron to change their mode of oscillation but also affects the resonant frequency of the generated oscillations.

The object of the present invention is to provide an improved device having a window which is capable of withstanding such high powers whilst at the same time reducing radio frequency reflections which might arise.

According to the present invention a device is provided for transmitting high frequency electromagnetic power having a window which is made of refractory material capable of transmitting high frequency power and having a single optic axis, said window being sealed to an apertured support, said optic axis being so orientated and the arrangement being such that radio frequency reflections which arise in said window and at the edge of the aperture in said support are substantially mutually cancelling.

In one example of the present invention the window is preferably made of sapphire and is sealed between a pair of apertured diaphragms and the optic axis of said window is arranged to be parallel to the axis along which power is transmitted through said window. In another example of the invention the window is sealed to a single diaphragm and in this case the optic axis of the window is arranged to be oblique to the axis along which power is transmitted through the window.

In order that the said invention may be clearly understood and readily carried into effect, it will now be described with reference to the accompanying drawings, in which—

Figure 1 illustrates in longitudinal sections a device in accordance with one embodiment of the invention, and

Figure 2 is a similar view of a device in accordance with another embodiment of the invention.

As shown in Figure 1 of the drawings, the reference numeral 1 illustrates a section of waveguide which may be connected to the resonant cavity of an electron discharge valve such as a klystron or magnetron and is pro-

2

vided with a window indicated at 2 which as shown is positioned in a plane normal to the axis of the waveguide 1 and which serves to seal the end of the waveguide 1 in a vacuum tight manner. The window 2 is made of crystalline refractory material having a single optic axis and which is capable of transmitting high frequency power. "Optic axis" is defined by Jenkins and White in "Fundamentals of Optics" (McGraw-Hill Publishing Co.) as being the one and only one direction through a crystal in which ordinary and extraordinary rays behave alike in all respects. In the present invention the optic axis of the window is so orientated in relation to the axis of the waveguide 1, i.e. the axis along which high frequency power is transmitted through the waveguide, that reflections which arise in said window and at the edges of a support for said window are substantially mutually cancelling. The window 2 is preferably made in the form of a disc of artificial sapphire (crystalline alumina), the disc being so formed for the embodiment shown in Figure 1 that the optic axis thereof is normal to the plane of said disc. The disc is mounted so as to close an aperture in a support, which in the embodiment shown in Figure 1 comprises a pair of apertured diaphragms 3 and 4 between which the disc is sealed, the rims 5 and 6 of the latter being in turn sealed as by welding to the end of the waveguide 1. The diaphragms 3 and 4 are made of a material having a coefficient of expansion lying in the range 5.7×10^{-6} such as a nickel-cobalt-iron alloy for example a material known by the registered trademarks "Kovar" or "Nicosel." The two diaphragms 3 and 4 and the window 2 are sealed together by applying a powdered glass, having a coefficient of expansion of about 5.7×10^{-6} such as a glass having a composition of about 67% SiO_2 , 21% B_2O_3 , 4½% K_2O , 4% Al_2O_3 and 3% Na_2O such as one known by the registered trademark "Kodial" around the edge of the disc 2 as indicated at 7 and to the adjacent metal surfaces of the diaphragms 3 and 4 and heating the assembly to about 900°C . to fuse the powdered glass. The diaphragm 3 is, as shown, spaced from the end of the waveguide 1 which is of the usual rectangular cross-section. The body 8 in which the waveguide 1 is formed is of circular cross-section and the end wall is provided with the usual annular high frequency choke 9, whilst the opposite longer walls of the waveguide 1 at their mid positions are provided with chamfered portions 10 of known form in order to reduce the danger of sparking between the end of the waveguide and the window 2. With such an arrangement with klystron or magnetron can be sealed in a vacuum tight manner and at the same time high frequency power can be transmitted through the window 2 into a further waveguide 11, the end of which is spaced from but disposed adjacent to the window 2. The body 12 in which the waveguide 11 is formed is provided with a high frequency choke 13 and the longer walls of the waveguide 11 are also provided with chamfered portions 14. The expansion of the sapphire disc in the plane of the disc is 5.7×10^{-6} per degree centigrade which matches the material known by the registered trademark "Kovar" sufficiently well for a sound hermetic seal to be produced. The expansion along the optic axis 15 of the sapphire disc is 6.4×10^{-6} which would cause a mismatch if it were in or near the plane of the disc. With such an arrangement it is found that reflections of high frequency power not only occur in the window 2 but also at the edges of the diaphragms 3 and 4. These reflections can be reduced by suitably orientating the optic axis 15 of the window 2 and by a suitable choice of the diameter of the apertures and the thickness of the window 2. These are the main factors which determine the reduction of reflection but other factors also enter into consideration, namely, the gap between the diaphragm 3 and the end of the waveguide 1 and the chamfered portions 10. The

optimum disposition of the various parts and their dimensions can best be determined by trial and error but in one example which is suitable for use with power of a frequency of 35,000 megacycles per second an arrangement having the following dimensions is found to give good results: The cross-sectional dimensions of the waveguide 1 are 0.280 inch $\times$ 0.140 inch; the thickness of the window 2 is 0.0055 inch with a dielectric constant of 9.4; the optic axis of the window is parallel to the axis of the waveguide 1; the thickness of diaphragms 3 and 4 is 0.010 inch; the diameter of the apertures in the diaphragms are 0.205 inch; the gap between the diaphragm 3 and the end of the waveguide 1 is 0.008 inch; the diameter of the choke 9 is 0.345 inch and the depth of the choke is 0.086 inch, and the radius of the chamfered portions 10 is 0.078 inch. The waveguide 11 which is coupled to the waveguide 1 may be spaced from the diaphragm 4 by a distance of 0.016 inch.

The dielectric loss of artificial sapphire is found to be rather less than that of the best low-loss glass at millimetre wavelengths. Moreover, the dielectric constant is more than twice as high (9.4 against 4.3) so that, the thickness for a matched window is less than half that of a glass window. The cooling of the window which mainly arises by convection from the outer face of the window is, therefore, at least twice as effective and this, coupled with the high melting point of sapphire which is over 2,000° C., affords a window with a power handling capacity which is more than twice that of a glass window.

In the embodiment of the invention shown in Figure 2 of the drawings where similar reference numerals have been given to similar parts, instead of sealing the window 2 between a pair of diaphragms as shown in Figure 1, the window 2 is only sealed to a single diaphragm 3 and in order to obtain cancellation of reflections occurring from said window and from the edge of the diaphragm 3 the optic axis, instead of being disposed parallel to the axis of the waveguide 1, as in the arrangement shown in Figure 1 is disposed obliquely to the axis as indicated by the dotted line 16. When the optic axis is not perpendicular to the plane of the sapphire disc then both ordinary and extraordinary rays are propagated in the disc and give rise to reflections having an appreciable difference of phase. These reflections combine to give an apparent equivalent reflecting plane which does not coincide with the central plane of the disc. Thus, by suitable adjustment of the optic axis this apparent reflecting plane can be made to coincide with the plane of the diaphragm so that a radio frequency match can be obtained with only one diaphragm. Preferably this one diaphragm is disposed on the vacuum side of the window so that the limiting peak power at which the window assembly will spark is considerably raised. The obliquity of the optic axis will not be found to be so great as appreciably to disturb the thermal expansion match to the diaphragm.

The dimensions of the parts for producing a substantial reduction in reflection with the arrangement shown in Figure 2 for a frequency of 35,000M/c.s. are as follows:

The cross-sectional dimensions of the waveguide 1 are 0.280 inch $\times$ 0.140 inch; the thickness of the window 2 is .006 inch with a dielectric constant of 9.4; the optic axis of the window makes an angle of 40° with the axis of the waveguide 1 and lies in that plane through the waveguide axis which makes an angle of 20° with the narrow side of the waveguide; the thickness of the diaphragm 3 is 0.010 inch; the diameter of the aperture in the diaphragm is 0.205 inch; the gap between the diaphragm 3 and the end of the waveguide 1 is .008 inch; the diameter of the choke 9 is 0.345 inch and the depth of the choke is 0.086 inch and the radius of the chamfered portions 10 is 0.078 inch. The waveguide 11 which is coupled to the waveguide 1 may be spaced from the diaphragm 3 by a distance of 0.022 inch.

What we claim is:

1. A device for transmitting high frequency power com-

prising a waveguide, a crystalline window disposed in a plane normal to the axis of the waveguide and made of a refractory material having a single optic axis and capable of transmitting high frequency power, an apertured support to which said window is sealed, said optic axis being so orientated to effect substantially mutual cancellation of radio frequency reflections which arise in said window and at the edge of the aperture in said support.

2. A device for transmitting high frequency power comprising a waveguide, a crystalline plane window disposed in a plane normal to the axis of the waveguide and made of a refractory material having a single optic axis and capable of transmitting high frequency power, an apertured support to which said window is sealed, said optic axis being so orientated to effect substantially mutual cancellation of radio frequency reflections which arise in said window and at the edge of the aperture in said support.

3. A device for transmitting high frequency power comprising a waveguide, a window disposed in a plane normal to the axis of the waveguide and made of sapphire, an apertured support to which said window is sealed, the optic axis of the window being so orientated to effect substantially mutual cancellation of radio frequency reflections which arise in said window and at the edge of the aperture in said support.

4. A device for transmitting high frequency power comprising a waveguide, a plane window disposed in a plane normal to the axis of the waveguide and made of sapphire, an apertured support to which said window is sealed, the optic axis of the window being so orientated to effect substantially mutual cancellation of radio frequency reflections which arise in said window and at the edge of the aperture in said support.

5. A device for transmitting high frequency power comprising a waveguide, a crystalline window disposed in a plane normal to the axis of the waveguide and made of a refractory material having a single optic axis and capable of transmitting high frequency power, an apertured support comprising two apertured metal diaphragms between which said window is sealed, said optic axis being orientated parallel to the axis along which said high frequency power is transmitted to effect substantially mutual cancellation of radio frequency reflections which arise in said window and at the edges of the apertures in said diaphragms.

6. A device for transmitting high frequency power comprising a waveguide, a crystalline plane window disposed in a plane normal to the axis of the waveguide and made of a refractory material having a single optic axis and capable of transmitting high frequency power, an apertured support comprising two apertured metal diaphragms between which said window is sealed, said optic axis being orientated parallel to the axis along which said high frequency power is transmitted to effect substantially mutual cancellation of radio frequency reflections which arise in said window and at the edges of the apertures in said diaphragms.

7. A device for transmitting high frequency power comprising a waveguide, a window disposed in a plane normal to the axis of the waveguide and made of sapphire, an apertured support comprising two apertured metal diaphragms between which said window is sealed, the optic axis of the window being orientated parallel to the axis along which said high frequency power is transmitted to effect substantially mutual cancellation of radio frequency reflections which arise in said window and at the edges of the apertures in said diaphragms.

8. A device for transmitting high frequency power comprising a waveguide, a plane window disposed in a plane normal to the axis of the waveguide and made of sapphire, an apertured support comprising two apertured metal diaphragms between which said window is sealed, the optic axis of the window being orientated parallel to the axis along which said high frequency power is trans-

mitted to effect substantially mutual cancellation of radio frequency reflections which arise in said window and at the edges of the apertures in said diaphragms.

9. A device for transmitting high frequency power comprising a waveguide, a crystalline window disposed in a plane normal to the axis of the waveguide and made of a refractory material having a single optic axis and capable of transmitting high frequency power, an apertured support comprising a single apertured metal diaphragm to which said window is sealed, said optic axis being orientated obliquely to the axis along which said high frequency power is transmitted to effect substantially mutual cancellation of radio frequency reflections which arise in said window and at the edge of the aperture in said diaphragm.

10. A device for transmitting high frequency power comprising a waveguide, a crystalline plane window disposed in a plane normal to the axis of the waveguide and made of a refractory material having a single optic axis and capable of transmitting high frequency power, an apertured support comprising a single apertured metal diaphragm to which said window is sealed, said optic axis being orientated obliquely to the axis along which said high frequency power is transmitted to effect substantially mutual cancellation of radio frequency reflections which arise in said window and at the edge of the aperture in said diaphragm.

11. A device for transmitting high frequency power

10

comprising a waveguide, a window disposed in a plane normal to the axis of the waveguide and made of sapphire, an apertured support comprising a single apertured metal diaphragm to which said window is sealed, the optic axis of the window being orientated obliquely to the axis along which said high frequency power is transmitted to effect substantially mutual cancellation of radio frequency reflections which arise in said window and at the edge of the aperture in said diaphragm.

12. A device for transmitting high frequency power comprising a waveguide, a plane window disposed in a plane normal to the axis of the waveguide and made of sapphire, an apertured support comprising a single apertured metal diaphragm to which said window is sealed, the optic axis of the window being orientated obliquely to the axis along which said high frequency power is transmitted to effect substantially mutual cancellation of radio frequency reflections which arise in said window and at the edge of the aperture in said diaphragm.
